JEREMIAH F. MARTIN, OF PAWTUCKET, RHODE ISLAND.

MOUNTING FOR SEWING-MACHINE HEADS.

Application filed June 21, 1922. Serial No. 569,979.

To all whom it may concern:

Be it known that I, JEREMIAH F. MARTIN, a citizen of the United States, and a resident of Pawtucket, in the county of Providence and State of Rhode Island, have invented new and useful Improvements in Mountings for Sewing-Machine Heads, of which the following is a full, clear, and exact description.

10 This invention relates to mountings for sewing machine heads and was primarily designed for use with sewing machine heads used for sewing filled bags.

15 The usual sewing machine provided for sewing the mouths of filled bags is provided with a massive base that carries the means for supporting the sewing machine head. To install these machines it is necessary to go to some considerable expense in 20 providing a base in the building upon which the sewing machine may be mounted. Such a device is expensive, takes up considerable room, and is very difficult to move from place to place. The head is usually rigidly 25 attached to the supporting means and when the machine is in operation, if the heavy bag is drawn too quickly through it, the needle breaks thus necessitating the stopping of the machine to make repairs. The 30 problem of eliminating the cost of installation, the expensive base for supporting the head and the trouble caused by the breaking of the needle by the too rapid movement of the filled bag through the machine is the 35 one which the inventor has solved.

The general object of this invention is the provision of a cheap, simple and efficient mounting for sewing machine heads that may be easily moved from place to place.

40 A further object of the invention is the provision of a mounting for a sewing machine head that depends from an overhead support and that is not rigid.

45 These objects are accomplished by providing an overhead support upon which a car is adjustably mounted, removably attaching to the car a guide arm upon which the sewing machine head is slidably mounted and providing in conjunction with the 50 guide arm means for raising and lowering the head.

These and other objects of the invention will be more clearly understood from the following detailed description and accompanying drawings, in which,

Figure 1 is a side elevation of the mounting and sewing machine head;

Figure 2 is a section along the line 2—2, Figure 1;

Figure 3 is a section along the line 3—3, 60 Figure 1.

Referring to the above-mentioned drawings, a track 10 is supported overhead in the building in which the sewing machine is to be used. On this track is a car assemblage 11 including a frame 12 and a grooved pulley 13 adapted to ride on the track 10. Attached to the bottom of the frame 12 is a hook 14. Depending from the hook 14 is a guide arm 15 which is detachably connected to the hook 14 by means of the eye 16.

Referring to Figure 1, a sewing machine head 17 of any usual construction is shown. In many other machine heads the base 19 75 of the head has a groove 20 extending across it. With such a mounting this groove is of use and the depending guide arms 15 is made of such a shape and size that it fits this groove. In this case the sewing machine head is shown slidably mounted on the guide arm 15 and it is retained in position on the guide arm by means of a motor 18 which is attached to the head by bolts 21. A cap 22 is attached to the lower end of the guide arm 15 by means of a screw 23 and serves as a means for preventing the head 17 from sliding off the guide arm. If the head is not provided with a groove in its base then a plate having a groove might be attached to the base of the head and thus a sewing machine head of any type might be slidably mounted on the guide arm.

Attached to the guide arm 15 are bearings 24 in which a shaft 32 is rotatably mounted. 95 Fixed to this shaft is a drum 29 and a worm gear 26. A worm 25 mounted to mesh with the worm gear 26 is supported by a plate 33 attached to the guide arm 15. A crank 28 is associated with the worm 25 for operating the same to rotate the worm gear 26. The upper end of a flexible belt 27 is attached to the drum 29 by means of a screw 30, and the lower end is attached to the head 17. This provides a means for raising and lowering the head for sewing bags of different length. In case it is desired to mount the cord supports on the sewing machine head, a bar 34 is positioned between the motor 18 and the head 17 and engaged by the bolts 21. To 110

each end of this bar, cord supports 35 may be attached.

The above description sets forth a sewing machine mounting which eliminates the expensive bases provided in conjunction with the ordinary sewing machine head and the cost of installation. By the use of the crank 28 the sewing machine head may be raised to any desired height to accommodate the bags 31. When it is desired to move the sewing machine head from one part of a building to another, by the detaching of the eye 16 from the hook 14 the head is ready for transportation. When in operation, if the bag 31 is moved too rapidly through the sewing machine thus exerting a pull on the needle, the head will swing, relieving the strain and thus saving the needle from destruction.

I would state in conclusion that while the illustrated example constitutes a practical embodiment of my invention, I do not limit myself strictly to the exact details herein illustrated since manifestly the same can be

considerably varied without departing from 25 the spirit of the invention as defined in the appended claim.

Claim:

A swingable sewing machine for sewing filled bags adapted to be suspended by an 30 overhead track and comprising a guide bar, means for supporting the guide bar upon the overhead track and providing for linear movement of the bar, means for removably connecting the bar with the supporting means 35 and including means to permit rotation and swinging of the bar, a sewing machine head 40 slidably mounted on the guide bar, means for connecting the sewing machine head to said bar and providing for vertical adjustment 45 of the head on the bar, said sewing machine head being adapted to straddle the unsupported tops of the bags and adapted to be rocked in a plurality of directions to conform to the movements of the tops of the bags 45 and support the tops of the bags when said bags are being sewed.

JEREMIAH F. MARTIN.
